No. 732,267.

PATENTED JUNE 30, 1903.

M. P. BOSS.
METALLURGICAL FURNACE.
APPLICATION FILED MAR. 26, 1902.

NO MODEL.

UNITED STATES PATENT OFFICE.

MARTIN PRIOR BOSS, OF SAN FRANCISCO, CALIFORNIA, ASSIGNOR TO THE HYDRO-CARBON SMELTING COMPANY, A CORPORATION OF WEST VIRGINIA.

METALLURGICAL FURNACE.

SPECIFICATION forming part of Letters Patent No. 732,267, dated June 30, 1903.

Application filed March 26, 1902. Serial No. 100,018. (No model.)

To all whom it may concern:

Be it known that I, MARTIN PRIOR BOSS, a citizen of the United States, residing at San Francisco, county of San Francisco, State of California, have invented certain new and useful Improvements in Metallurgical Furnaces, of which the following is a specification.

My invention relates to a furnace adapted within a single structure to reduce a metal from its calcined ore, to oxidize the metal, and otherwise act upon it to free it from its accompanying impurities.

My invention consists in the construction and arrangement of the chambers in which the metallurgical operations are conducted; also, to the means employed for producing the required reducing and oxidizing atmospheres in said chambers; also, to the means employed for introducing air-currents below the level of the molten metal in the oxidizing-chamber; also, to the employment in the oxidizing-chamber and in connection with introduced currents of a bed or hearth formed of a material or materials which will coat with the metal under treatment; also, to the general construction of the furnace.

The objects of my invention are, primarily, to decrease the cost of reducing a metal from its ore by effecting all of the metallurgical operations subsequent to calcination in a single structure, thereby saving in the cost of handling, preventing loss of heat, &c., and, secondarily, through the construction of the oxidizing-chamber and by reason of its chemically active bed and the employment of air-blasts to produce a very rapid and effective oxidation of the metal under treatment in the oxidizing-chamber.

The accompanying drawings will serve to illustrate my invention and in which similar numerals indicate like parts.

Figure 1 is a longitudinal section of the furnace. Fig. 2 is a plan view of the top of the reducing-chamber of the furnace and horizontal section through the oxidizing-chamber. Fig. 3 is a vertical section of the oxidizing-chamber on the line X X of Fig. 1. Fig. 4 is a vertical section through the reducing-chamber on the line Y Y of Fig. 1.

My improved furnace consists, essentially,

of two chambers—5, a reducing-chamber, and 6 an oxidizing-chamber. The reducing-chamber is provided with a crown 7 and a conical hearth 8. The oxidizing-chamber is provided with a crown 9 and a horizontal hearth 10, which forms a basin. At the forward end of the oxidizing-chamber is located a chimney-flue 11. The hearth 8 of the reducing-chamber and hearth 10 of the oxidizing-chamber are supported upon arches 12, which serve to form a cave under the hearths.

Situated over the reducing-chamber is a trackway 13, on which is mounted a hopper-car 14, by which calcined ore is brought to the reducing-chamber and discharged into the reducing-chamber through the opening 15 in the top of the chamber.

The oxidizing-chamber is provided with a bed 16, which may be made of ore such as is under treatment, of matte of partially-refined ore, or pig metal, and with these materials may be mixed any fluxing material—such, for instance, as dolomite.

Situated in the top of the reducing-chamber and oxidizing-chamber are a series of hydrocarbon-burners 17, by means of which a hydrocarbon gas mixed with air may be delivered into the furnace through the pipes 18 and 19, which communicate with the sources of supply. The pipes 18, which are the blast-mains, also communicate with air-twyers 20, which project, as is shown in Figs. 2 and 3, from the sides of the furnace into the bed of the furnace, so that the air-blast is discharged under the molten metal on the hearth or bed. In order to protect these twyers against clogging by a sudden chill of the metal, I carry the branches 21 from the hydrocarbon-feed pipe into them. These branches are not intended in the ordinary operation of the furnace to be lighted, but may be lighted to keep the twyers clear when required or to heat the air passing in through the twyers.

22 is a slag-dam in the oxidizing-chamber; 23, slag-door; 24, doors through which the fluid metal may be drawn from the chamber.

The operation of my device is as follows: The calcined ore is discharged into the reducing-chamber from the hopper-car 14 and forms a mound in the chamber, as indicated in the dotted line, Fig. 1. As the ore is

melted under the action of the hydrocarbon-burners and air-blast, as well as by the decomposition of the combustible materials in the ore, the slag and metal flow from the hearth 8 of the reducing-chamber into the oxidizing-chamber 6. Here the slag is removed through the slag-door 23, the metal flowing under the slag-dam 22. As the metal moves forward in the oxidizing-chamber it is refined and in the process of refining makes a continuous up-and-down movement. In order to aid the refining and also to keep the metal in motion, so as to more effectually remove oxidizable materials from it, it is subjected to a continuous air-blast from the twyvers 20. Preferably this air-blast should be heated, although good results may be obtained without heating it.

It will be observed from the drawings that the hydrocarbon-burners are so disposed that the flames delivered from them will be freely developed within the furnace without coming in contact with the material in the furnace. I prefer this system of heating, as I find that better results may be obtained from radiated heat than from heat due to the impact of the flame. I, however, do not wish to limit myself to the employment of burners so situated and used, as other heating means may be substituted. Neither do I wish to limit myself to the employment of a conical hearth in the reducing-chamber, although I prefer to use such a hearth, as movement of the material in the chamber toward the oxidizing-chamber is facilitated by such construction.

Having thus described my invention, I claim—

1. A metallurgical furnace, comprising a chamber, means for creating a reducing atmosphere in said chamber, a second chamber connected to the first-named chamber, a supplemental bed located upon the hearth of said chamber, means for creating an oxidizing atmosphere in said chamber, and means for delivering an air-blast above the hearth of said oxidizing-chamber and below the normal level of the melted metal discharged into said chamber.

2. A metallurgical furnace comprising a chamber, means for creating a reducing atmosphere in said chamber, a second chamber connected to the first-named chamber, means for creating an oxidizing atmosphere in said chamber, a supplemental body of material located upon the hearth of the second-named chamber composed of materials which will coact with the substance under treatment, and means for delivering an air-blast into said body of material.

3. A metallurgical furnace comprising a chamber provided with a conical hearth, means for creating a reducing atmosphere in said chamber, a second chamber having its hearth shaped to form a basin, means for creating an oxidizing atmosphere in said chamber, and an exit-flue leading from the oxidizing-chamber.

4. A metallurgical furnace comprising a chamber, means situated in the top of said chamber for introducing gas and air, whereby a reducing atmosphere may be created, a second chamber, connected to the first-named chamber, means situated in the top of said chamber for introducing gas and air, whereby an oxidizing atmosphere may be created, and means for introducing an air-blast into the bottom of the oxidizing-chamber.

5. In a metallurgical furnace, a chamber, means for creating an oxidizing atmosphere in said chamber, a supplemental body of material located upon the hearth of such chamber which will coact with the substance under treatment, and means for introducing an air-blast into such body of material.

6. In a metallurgical furnace, an oxidizing chamber, a supplemental body of material which will coact with the substance under treatment situated on the hearth of said chamber, means for creating a free development of flame in the upper portion of said chamber whereby an oxidizing atmosphere is created, and said flame not brought in contact with the material under treatment; and means for introducing air-currents into the body of material on the hearth of the chamber.

7. In a metallurgical furnace, a chamber provided with means for creating an oxidizing atmosphere, said means consisting of hydrocarbon-gas and air burners, adapted to discharge their flames in a downward direction from each side of the top of the chamber whereby free development of flame is permitted, but not brought in contact with the material under treatment; and air-twyers adapted to discharge air-currents laterally into said chamber a short distance above the hearth of said chamber and below what would be the normal horizontal level of the material under treatment in the chamber.

8. In a metallurgical furnace, the combination with a chamber and its hearth, of a supplemental body of material located on said hearth which will coact with the substance under treatment, and means for discharging air-currents into said body of material.

9. In a metallurgical furnace, a chamber having a conical bed and an arched top, a second chamber connected at one end to the first-named chamber and having a horizontal hearth and connected at its opposite end to an exit-flue.

10. In a metallurgical furnace, a chamber having a conical hearth and an arched top, a second chamber connected to the first-named chamber at one end and having a horizontal hearth situated below the plane of the hearth of the first-named chamber and connected at its opposite end to an exit-flue.

11. In a metallurgical furnace, a chamber having a conical hearth and an arched top with an opening therein through which the material to be treated may be fed into the furnace, means for creating a reducing atmosphere in said chamber, a second chamber

connected to the first-named chamber at one end and having its hearth in a lower horizontal plane than the hearth of the first-named chamber and connected at its opposite end to 5 an exit-flue.

12. In a metallurgical furnace, a chamber having a conical hearth, an air-cave under said hearth, a crown located at a considerable distance above the hearth, means for creating a reducing atmosphere in said chamber, a second chamber connected at one end to the first-named chamber and provided with a horizontal hearth located at a lower plane than the hearth of the first-named chamber 15 and provided with a crown whose distance above the hearth is less than the distance above the hearth of the crown of the first-

named chamber, and said second chamber connected at its opposite end to an exit-flue.

13. In a metallurgical furnace, a chamber, 20 a supplemental bed upon the hearth of said chamber formed of a material or materials which will combine or react with the material under treatment, means for creating an oxidizing atmosphere in said chamber, and means 25 for introducing air into said bed and below the material under treatment.

In testimony whereof I affix my signature in the presence of two witnesses.

MARTIN PRIOR BOSS.
